GARMENT PRESSING MACHINE

Walter A. Hoch, Forest Hills, N. Y., assignor to
New York Pressing Iron Co., Inc., New York,
N. Y., a corporation of New York

Application August 31, 1939, Serial No. 292,761

6 Claims. (Cl. 121—38)

My invention relates to a new and improved pressing machine.

One of the objects of the invention is to provide a power-actuated machine for pressing garments, having an improved two-hand control and improved means for holding the press closed under pressure, if the two-hand control is released after the press-head has moved a predetermined distance towards the buck.

Another object of the invention is to provide a pressing machine which is operated by a suitable motor, such as a piston and cylinder, and having improved means which are wholly independent of a by-pass valve or valves for maintaining the pressure, after the head of the press has been substantially or wholly closed.

Another object of the invention is to provide a machine of this type, wholly independent of a by-pass valve or valves, whereby the machine will be opened if the operator releases one or both of the manual controls, before the machine has been substantially or wholly closed.

Another object of the invention is to provide a machine of this type having improved exhaust means for opening the press, after the pressing operation has been completed.

Another object of the invention is to provide a machine having a minimum number of parts and which will be simple to construct and to operate.

Another object of the invention is to provide an improved control system whereby one operator may operate a single press or operate a plurality of presses.

Other objects of my invention will be set forth in the following description and drawings which illustrate certain preferred embodiments, it being understood that the above statement of the objects of my invention is intended generally to explain the same, without limiting it in any manner.

Fig. 1 is a side elevation, partially in section, of the improved press. The full-line positions of certain parts of the press illustrate the closed position of the press, and the broken-line positions of said parts correspond to the open position of the press.

Fig. 2 is a top view of the actuating cylinder of the press shown in Fig. 1, and certain auxiliary parts, taken along a line which is perpendicular to the arrow which is designated by 2 in Fig. 1.

Fig. 3 is a top plan view of the table of the press, taken along the line 3—3 of Fig. 1.

Fig. 4 is a diagrammatic view of the control system which is used in connection with the press which is illustrated in Fig. 1.

Fig. 5 is a diagrammatic view of the improved control system, as applied to two presses which are operated in tandem.

Fig. 6 is a top plan view of the table of the tandem-operated presses, according to the first embodiment.

The invention is shown as applied to a press of conventional construction and it is not limited to any particular type of press. The press has a frame 1, a buck 2, a head 3 and a table 4. The head 3 is connected to a pivoted frame which includes an arm 5. Said arm 5 is pivotally connected at 6, intermediate its ends, to the frame of the machine. The pivoted frame of the head 3 also includes an arm 7, which is rigid with said frame. The arm 5 has a boss 8. The arm 7 is pivotally connected at 9 to a link 10 which is pivotally connected at 11 to a sector 12. The sector or knee lever 12 is pivotally connected at 17 to a second sector or knee lever 18. The second sector 18 is pivotally connected at 19 to a link 20, which is pivotally connected at 21 to the frame of the machine. The first sector 12 is pivotally connected at 14 to a link 15 which is pivotally connected at 16 to the base of the frame 1.

In Fig. 1, the full-line positions of the links 10 and 20 correspond to the closed position of the press and the broken-line position of the sector 18 corresponds to the open position of the press.

The tension spring 22 has one end connected to a hook 23 which is rigidly connected to the frame 1. The other end of said tension spring 22 is connected at 24 to the link 10. The tension spring 22 merely serves to open the press when the exhaust is opened. The tension spring 22 can be connected to any of the moving parts of the press. The left-hand end of the spring 22 can be connected to the base of the frame at 16. The sector 18 is also pivotally connected to a transverse rod 25 which is located within a clevis 26, which is rigidly connected to the piston rod 27. The piston rod 27 is connected to a piston 28, which reciprocates in a cylinder 29. The clevis 26 is guided between stationary guides 30 which are rigidly connected to the frame of the machine. Tension springs 31 and 31a normally keep the piston in its retracted position, which is shown in broken lines in Fig. 1, and which corresponds to the open position of the press. Each of said springs 31 and 31a has one end thereof fixed to a respective lug of cylinder 29, and its other end connected to a respective end of rod 25, as shown in Fig. 2.

Referring to Fig. 4, this shows an inlet pipe 32 which may be connected to a suitable source of fluid under pressure. This fluid is preferably air. The pipe 32 has an extension 33 which is connected to a first valve-casing 34. This casing 34 has an outlet pipe 35, which is connected to a second valve-casing 36. The valve-casing 34 has an exhaust outlet or pipe 34a and the valve-casing 36 has an exhaust outlet or pipe 36a. A valve stem 37 is movably located in the valve-casing 34. The valve-stem 37 has valves 37a and 37b and it is actuated by a compression spring 39 to the normal position illustrated in Fig. 4. The valve-casing 34 has spaced seats for said valves 37a and 37b. In this normal position the valve 37b abuts its seat and it prevents the compressed air from passing into the pipe 35, and the valve 37a clears its seat so that air can exhaust freely from the valve-casing 34, above the seat of valve 37b. The valve-casing 36 is provided with a valve-stem 38 which has valves 38a and 38b. Said valve-casing 36 also has a spring 39a. The valve-casings 34 and 36 and their respective valves and controls are identical. The valve-casing 36 has an outlet pipe 40. In the normal positions of the valves 38a and 38b, the valve 38b prevents the compressed air from passing through the valve-casing 36 to the pipe 40.

In said normal position the valve 38a clears its seat so that air can exhaust freely from the valve-casing 36 through the outlet 36a, above the seat of valve 38b. The valve stems 37 and 38 are provided with any suitable and separate controls. These controls may be manually controlled levers 41 and 42 which are respectively pivotally mounted at 41a, 42a. These levers may be turned by means of push buttons 43, 43a.

Since the casings 34 and 36 and their respective valves are located in series, it is necessary to depress both valve-stems 37 and 38, in order to admit compressed air into the pipe 40. The pipe 40 is provided with a branch 44, which is connected to the valve-casing 45 of a first pilot motor. Said valve-casing 45 has a first pilot piston 46, which is normally maintained in the position shown in Fig. 4, by means of a compression spring 47. The valve 46 has a spindle 46a, one of whose ends abuts a lever 48, which is pivotally connected to the frame of the machine at 49. In the normal positions of the parts, the lever 48 is in the full-line position shown in Fig. 4. The lever 48 is maintained in said normal position by means of a compression spring 50. The outlet end of the pipe 40 is connected to a valve-casing 51. A valve 52, having a spindle 53, is located in said casing 51. The spindle 53 is connected to an actuating piston 54.

A compression spring 55 maintains the piston 54 in the normal position shown in Fig. 4, in which valve 52 clears its seat. The valve-casing 54 is connected by means of a pipe 56 to the cylinder 29, intermediate the ends of said cylinder.

The port 56a of the pipe 56 is spaced from the median lateral plane of the cylinder 29. The valve-casing 51 is connected to a pipe 57. Said pipe 57 is connected to pipes 58 and 59, through a coupling 60. The inner wall of said coupling 60 is provided with an annular projection 61 so as to form a constricted opening. This constricted opening may be formed in any other manner and its purpose is to retard the flow of the air through the pipe 57. The cross-sectional area of said constricted opening is less than the respective cross-sectional areas of the bores of the pipes 57, 58 and 59, and said pipes 57, 58 and

59 and the other pipes shown in Fig. 4 may have bores of substantially equal cross-sectional areas. One end of the pipe 59 is connected to the inner end of the cylinder 29 by means of a port 59a. The pipe 58 is connected to an exhaust valve-casing 60a, which has an outlet 61b and a valve 62. The valve 62 has a spindle 63c which is raised, together with the valve 62, by means of a compression spring 63, when the lever 48 is turned from its normal position to the broken line position shown in Fig. 4, so as to prevent the air from exhausting out of valve-casing 60a. The force of the compression spring 50 is greater than the force of the compression spring 63, so that the valve 62 is normally held away from its seat, in the position shown in Fig. 4.

When the valve 62 is in said normal position, air can exhaust out of the valve-casing 60a through the outlet 61b. When the lever 48 is turned to the broken-line position, the valve 62 is moved against its seat so as to prevent the air from exhausting through the outlet 61b. The pipe 59 is also connected, through a coupling 64 (also having a constricted bore portion) to a valve-casing 65. The constricted bore portions of couplings 60, 64, and 70 are of identical area, and said couplings are generally the same in all respects. Said valve-casing 65 has a valve 66, which is normally held in the position shown in Fig. 4, by means of a compression spring 67, so that valve 66 normally abuts its seat. Hence the compressed air cannot flow through the valve-casing 65, until the lever 48 has been moved to its broken-line position. When this is done, the valve 66 is moved away from its seat so that communication is established between the pipe 59 and the branch pipe 32a of the inlet pipe 32.

The pipe 57 is also connected to a branch pipe 68, which is connected to a pipe 69 by means of a coupling 70. The pipe 69 is connected to the valve-casing 71 of a second pilot-motor, in which a second pilot piston 72 is located. A compression spring 73 holds the second piston 72 in the normal position shown in Fig. 4. One end of the spindle 72a of the piston 72 then abuts the upper wall of the lever 48. The pipe 69 is also connected to a branch pipe 74, which is connected to the valve-casing 75 of the manually controlled exhaust valve 77. Said valve-casing 75 has an exhaust outlet 76. A compression spring 78 holds valve 77 against its seat in the normal position shown in Fig. 4, thus normally preventing the air from exhausting from the valve-casing 75. The valve 77 can be depressed so as to clear its seat and to permit the air to exhaust out of the valve-casing 75, by means of a manually controlled lever 79, which is pivotally mounted at 80.

The operation of the device is as follows:

At the beginning of the closing of the press and during a predetermined period, it is necessary for the operator to depress the control buttons 43 and 43a and to hold said buttons in their depressed condition, in order to admit compressed air into the pipe 40. This requires the use of both hands of the operator. The compressed air flows rapidly through the branch pipe 44, which has no constriction, so as to operate the first pilot piston 46. The first pilot piston 46 is thus automatically depressed so as to turn the lever 48 to its broken-line position, and the spring 63 raises the valve 62, so as to prevent the air from exhausting through the outlet 61b. This operation is performed very rapidly, so as to prevent any substantial loss of compressed air. While the air is flowing through the pipe 44, it is also

flowing through the pipe 40 into the casing 51 and out of casing 51 through the pipe 57. Of course, when the valve-spindles 37 and 38 are manually depressed, their respective valves 37a and 38a abut their respective seats in the valve-casings 34 and 36, in order to prevent the air from exhausting through the outlets 34a and 36a.

The constriction which is provided by the coupling 60 retards the flow of air into the pipe 59. Hence the first pilot piston 46 is operated so as to turn lever 48 to its broken-line position, thus permitting spring 63 to move the valve 62 against its seat, before there is any substantial flow of compressed air into the cylinder 29, and before any substantial movement of the motor-piston 28.

Some of the compressed air flows through the pipe 68 into the casing 71, this flow of the air being retarded by the coupling 70. The second pilot-piston 72 is therefore operated almost simultaneously with or shortly after the first pilot-piston 46, and the spindles of both pilot-pistons 72 and 46 therefore maintain the lever 48 in its broken line position, thus moving valve 66 away from its seat. The compressed air can therefore flow from branch pipe 32a into the pipe 59, to the port 59a of the cylinder 29. The piston 28 is thus operated at regulated speed, so as to close the press. The operator must maintain the buttons 43 and 43a in their depressed and operative positions until the piston 28 has passed beyond and cleared the port 56a of the pipe 56, as shown in broken lines in Fig. 4.

If the operator releases one of the control buttons 43 and 43a before the piston 28 has reached said broken-line position, the valves of the casings 34 and 36, or one of said valves, are moved back to the normal position shown in Fig. 4. The air will therefore exhaust out of the valve-casing 34 or 36, whose control button has been released. This exhaust is very rapid through pipe 44 and the compression spring 47 will therefore rapidly move the piston 46 back to its normal position, and the spring 50 will rapidly move the lever 48 back to its normal position, thus moving the valve 62 away from its seat and permitting the air to exhaust out of the casing 60a. The air can also exhaust out of the casing 71 through the pipes 69, 68, 57, the valve-casing 51 and the pipe 40 and through one of the valve-casings 34 and 36, if one or both buttons 43 and 43a is released.

The tension springs 22, 31 and 31a will then operate to open the press.

As soon as the piston 28 has moved to the broken-line position shown in Fig. 4, the compressed air flows through the pipe 56 to the valve-casing 51, thus actuating the piston 54 and moving the valve 52 against its seat. The supply of compressed air to the cylinder 29 through the pipe 40 is then cut off but the air pressure is continued through the pipe 32a, the valve-casing 65 and the pipe 59. The pipes 40 and 32 are respectively inlet pipes which supply fluid under pressure to the cylinder 29 at the inlet of said cylinder 29, through respective intermediate connecting means. The compressed air or other fluid which is thus supplied may be designated as motive fluid, as it operates the piston 28. The press is thereupon either maintained in the closed position or it is moved slowly to final closing position. For example, the pistons 72, 54 and the like can be replaced by diaphragms. Whenever I refer to "means" in the claims, said designation includes one device or a plurality of devices. The speed of movement of the piston 28 is regulated

by the needle valve N, which regulates the flow of air out of the front end of the cylinder 29.

Therefore all by-pass valves and mechanical means for operating the same are wholly eliminated, because the air is supplied to the motor cylinder 29 immediately through two branch lines when the control buttons are actuated, and air pressure is maintained through one of said branch lines, even when the control buttons are released, if the distance of head 3 from buck 2 is less than a predetermined distance. When the control buttons 43 and 43a are released, after the piston 28 has reached its broken-line position, the air can exhaust out of the cylinder 46, but it cannot exhaust out of the casing 71 as long as valve 71 abuts its seat, so that the piston 72 maintains the lever 48 in its broken-line position so that the valve 62 is held in its closed position by spring 63.

After the completion of the desired pressing period, the operator actuates the lever 79 so as to depress the valve 71. The compressed air which is located in the casing 71 above the piston 72 can then exhaust through the outlet 76 of the casing 75. Both branch lines are thereupon exhausted, so that the opening spring or springs 22 and 31 and 31a can then open the press.

The system shown in Fig. 5 is the same in principle as that shown in Fig. 4. Similar parts have therefore been designated by the same reference numerals in Figs. 4 and 5. For example, Fig. 5 shows two pairs of control buttons 43 and 43a, one pair for each machine.

The exhaust lever 81 of Fig. 5, which has the same function as exhaust lever 79 of Fig. 4, controls the exhaust of machine No. 2. The exhaust lever 82 of Fig. 5 controls the exhaust of machine No. 1. The exhaust lever 83 also controls the exhaust of machine No. 2. The casing which is associated with exhaust lever 83 is connected to pipe 69, by means of an intermediate pipe 85, so that the casing 71 of machine No. 1 is connected by means of said pipe 85 to the casing which is associated with exhaust lever 83. In the same manner the casing which is associated with said lever 81 is connected by means of an intermediate pipe 86 to the casing 71 of machine No. 2.

The two machines shown in Fig. 5 have respective tables, each table being provided with a pair of control buttons 43 and 43a. However the table for each machine also has a pair of manually operable release or exhaust levers so that the operator can open either machine without moving from the table of the particular machine at which he is then stationed.

While the improved control and operating system has been shown as applied to a garment press which has a stationary buck and a head which is movable towards said buck and away therefrom, said system can be utilized for various types of presses and for various types of garment presses.

It will be noted that since equal fluid pressure is exerted at the opposite faces of valve 66, the spring 67 will bias said valve 66 to a normally closed position, until the pilot device 46 is actuated. The invention is not restricted to any specific means for manually or automatically operating the various valves, as the essential feature of the invention, in its broader aspect, comprises the control operations described herein.

For convenience, certain of the parts have been designated by reference numerals in these claims, but such claims are not restricted to the

specific parts or means which have been thus designated.

Likewise the inlet-and-exhaust devices in casings 34 and 36 may have exhaust valves which are not connected to the respective inlet valves 37b and 38b. The invention also includes numerous valuable sub-combinations which can be used independently of the complete device illustrated herein.

I have described preferred embodiments of the invention, but numerous changes and omissions can be made without departing from its spirit.

I claim:

1. A press which has a buck and a head which is movable towards said buck and away from said buck, a fluid-operated motor connected to said head and adapted to actuate said head, a first branch line and a second branch line respectively adapted to receive motive fluid under pressure, the first branch line being connected to said motor through spaced and separately operable inlet-and-exhaust devices, said first branch line also including a first control valve 52 which is biased to the normally open position, a first pilot device 54 connected to the first control valve 52 and adapted to close said first control valve 52, automatic means adapted to supply motive fluid to the first pilot device 54 when the head is at a predetermined distance from the buck so as to close the first branch line from the motor, the second branch line being connected to the motor through a second control valve 66 which is biased to a normally closed position, said second control valve 66 being located in a casing 65, said casing 65 being connected above the valve 66 to the first branch line after the first valve 52, a second pilot device 46 connected to the first branch line in advance of first control valve 52 and after said inlet-and-exhaust devices, said second pilot device 46 being operable by the motive fluid in the first branch line, said second pilot device 46 being associated with operating means adapted to open the second control valve 66 when said second pilot device 46 is operated by the motive fluid in the first branch line, a first exhaust valve 62 connected to the first branch line after the first control valve 52, said first exhaust valve 62 being biased to normal closing position, said operating means being adapted to hold said first exhaust valve 62 open until said operating means are actuated by said second pilot device 46, a third pilot device 72 connected to the first branch line at a point between the first control valve 52 and the first exhaust valve 62, said third pilot device 72 being located and operative to actuate said operating means in the same direction as the second pilot device 46 so as to hold the second control valve 66 open and to permit the closing of the first exhaust valve 62 when said third pilot device 72 is actuated, a manually operable exhaust valve 62 connected to the casing of the third pilot device 72.

2. A device according to claim 1 having first means adapted to diminish the rate of flow of the motive fluid between the first control valve 52 and the first exhaust valve 62 and also having second means adapted to diminish said rate of flow between the motor and the second control valve 66 and also having third means adapted to diminish said rate of flow from the casing of first control valve 52 to the casing of third pilot device 72, in comparison with the rate of flow of said fluid to the casing of second pilot device 46.

3. In a press, the combination of a movable

press-part, a fluid-operated motor connected to said movable press-part, said motor operating said press-part when fluid under pressure is supplied to said motor, a first branch-line and a second branch-line, each branch-line having an inlet end which is connected to a source of fluid under pressure, each branch-line having an outlet end which is connected to said motor to supply fluid under pressure to said motor when the respective branch-line is open, each branch-line having a valve, the valve of the first branch-line being biased to normal open position, the valve of the second branch-line being biased to normal closed position, pilot mechanism, said pilot mechanism having a first means operative to open the valve of the second branch-line, and a second means operative to close the valve of the first branch-line, said first branch-line having a pair of manually controlled valves which are arranged in series, means interconnecting the first means of the pilot mechanism with the pair of valves to render the first means operative only upon the actuation of the pair of valves to working position, means responsive to a predetermined movement of said press-part to render the second means of the pilot mechanism operative, and means for maintaining the valve of the second branch line open after the predetermined movement.

30. 4. In a press, the combination of a movable press-part and a fluid-operated motor connected to and adapted to actuate said movable press-part, a first inlet branch-line and a second inlet branch-line which are respectively connected to a source of fluid under pressure and which are respectively connected to said motor through respective valves to the inlet of said motor in order to supply motive fluid thereto, pilot mechanism, said pilot mechanism having a first means operative to open the valve of the second branch-line, and a second means operative to close the valve of the first branch-line, said first branch-line having a pair of manually controlled valves, means interconnecting the first means of the pilot mechanism with the pair of valves to render the first means operative only upon the actuation of the pair of valves to working position, means responsive to a predetermined movement of said press-part to render the second means of the pilot mechanism operative, and means for maintaining the valve of the second branch line open after the predetermined movement.

55. 5. A combination according to claim 4 in which the second branch-line has a manually operable exhaust valve and the first branch-line has a second exhaust and normally open exhaust valve, and automatic pilot means operable to close the second exhaust valve substantially when fluid is admitted to the motor.

60. 6. A pressing machine comprising a movable press-part, a cylinder having a piston which is connected to said press-part and which is adapted to actuate said press-part, said cylinder having a cylinder-inlet to receive the fluid for operating said piston, a first branch-line having one end thereof connected to a source of fluid and having the other end thereof connected to said cylinder-inlet, said first branch-line having a first control-valve therein, the second branch-line having one end thereof connected to a source of fluid and having the other end thereof connected to said cylinder-inlet, the second branch-line having a normally closed second control-valve therein, first fluid-operated pilot-means adapted to open the second control-valve and to maintain

said second control-valve open as long as said first pilot-means is connected to a source of fluid under pressure, the first pilot-means being connected to the first branch-line in order to receive motive fluid therefrom, second fluid-operated pilot-means adapted to close the first control-valve and to maintain said second control-valve closed as long as said second pilot-means receives fluid under pressure, the second pilot-means being connected to a port of said 10

cylinder, said port being located rearwardly of the cylinder-inlet so that fluid under pressure is admitted from the cylinder to the second pilot-means only after the piston has cleared said port 5 in the operating stroke of said piston away from said cylinder-inlet, and manually controlled means adapted to exhaust said cylinder and said pilot-devices.

WALTER A. HOCH.
